UNITED STATES PATENT OFFICE.

DANIEL W. HARRIS, OF PLATTE CITY, MISSOURI.

INNER TUBE FOR AUTOMOBILE-WHEELS.

1,047,803.

Specification of Letters Patent.

Patented Dec. 17, 1912.

Application filed April 3, 1912. Serial No. 688,252.

To all whom it may concern:

Be it known that I, DANIEL W. HARRIS, a citizen of the United States, residing at Platte City, in the county of Platte and State of Missouri, have invented certain new and useful Improvements in Inner Tubes for Automobile-Wheels, of which the following is a specification, reference being had therein to the accompanying drawing.

10 This invention relates to elastic inner tubes for tires, and has for its object the production of an efficient metallic inner tube which will readily yield when coming in engagement with an obstruction.

15 Another object of this invention is the production of an efficient metallic spring tire of the spiral type which will perform all of the functions of a pneumatic inner tube.

With these and other objects in view, this 20 invention consists of certain novel constructions, combinations, and arrangements of parts, as will be hereinafter fully described and claimed.

In the drawings: Figure 1 is a central 25 vertical section of the wheel showing the spiral tube placed within the tire. Fig. 2 is a transverse section through the tire.

By carefully considering Fig. 1, it will be seen that the resilient tube comprises a 30 spiral structure having one convolution wound upon and seated upon the adjacent convolution so as to allow the tube to yield as the tire passes over an obstruction.

By carefully considering Fig. 2, it will 35 be seen that the usual rim 1 is employed which rim is provided with a plurality of parallel circumferential grooves 2 in which grooves are seated the side edges of the first convolution or base convolution of the 40 spiral tube structure 3. As stated above, one convolution of the spiral inner tube is wound upon the adjacent convolution as illustrated in cross section in Fig. 2, and it will be seen that the side edges of the sec- 45 ond convolution rest upon the bulged sides of the first convolution. The side edges of the third convolution rest upon the bulged sides of the second convolution thereby allowing the respective convolutions of the 50 spiral inner tube to readily yield one upon the other, both transversely and longitudinally. When constructing the spring inner

tube, the second convolution extends down practically one-half an inch below the top of the inner or first convolution, and the 55 third convolution in like manner overhangs the second convolution. Of course, when pressure is brought to bear upon the tire the different spiral sections may telescope over each other, and thereby force the side 60 edges of one convolution for quite a distance upon the sides of the other convolution as illustrated clearly in Fig. 2. It should be noted that when the spiral convolution is first wound that the same is wound in the 65 relation as just described.

By carefully considering Figs. 1 and 2 it will be seen that the outer casing 6 will be supported away from the rim 1 of the wheel and that the tire will not become flat should 70 the outer casing 6 become perforated for the reason that the spiral tube structure 2 will at all times hold the casing in its proper position.

From the foregoing description it will be 75 readily obvious that a very efficient and durable inner tube has been produced which may be made of very light material, and while being formed of spring metal will form a very efficient resilient means to take 80 the place of the ordinary pneumatic tube now in use. Owing to the elasticity of the spring inner tube, it will be seen that the same will readily conform to the contour of the rim as well as to the outer tire tread. 85 Furthermore, owing to the fact that the side edges of the different convolutions are so mounted upon the adjacent convolutions the sides of the tire will be protected from being cut by the side edges of the several convolutions as is clearly illustrated in Fig. 2, owing 90 to the fact that these side edges of the convolutions are spaced from the inner face of the tire.

What is claimed is:—

A device of the class described comprising a rim having a plurality of parallel circumferential grooves formed therein, a spiral inner tube formed of spring metal and being substantially circular in cross section, 100 the inner convolution of said spiral having its side edges fitted within said grooves in said rim and the other convolutions of said spiral wound upon the first convolution

whereby the side edges of the second convolution will engage the bulged sides of the first convolution, and the side edges of the third convolution will engage the bulged 5 sides of the second convolution for efficiently holding the several convolutions in their respective operative positions.

In testimony whereof I hereunto affix my signature in presence of two witnesses.

DANIEL W. HARRIS.
